(57) **CLAIM**

The ornamental design for a motorcycle tail light, as shown and described.

DESCRIPTION

FIG. 1 is a perspective view of the motorcycle tail light.

FIG. 2 is a front elevation view thereof.

FIG. 3 is a rear elevation view thereof.

FIG. 4 is a first side view thereof.

FIG. 5 is a second side view thereof, opposite the first side.

FIG. 6 is a top side view thereof; and,

FIG. 7 is a bottom side view thereof.

The rear surface and mounting flanges of the motorcycle tail light shown in broken lines form no part of the claimed design.

1 Claim, 7 Drawing Sheets
